UNITED STATES PATENT OFFICE.

WILLIAM ACKIN MOORE, OF WASHINGTON, DISTRICT OF COLUMBIA.

COMBINED DOOR-PLATE, KNOCKER, AND LETTER-RECEIVER.

SPECIFICATION forming part of Letters Patent No. 359,458, dated March 15, 1887.

Application filed December 15, 1886. Serial No. 221,596. (No model.)

To all whom it may concern:

Be it known that I, WILLIAM ACKIN MOORE, of Washington city, in the District of Columbia, have invented a new and useful Improvement 5 in a Combined Door-Plate, Knocker, and Letter-Receiver, of which the following is a specification.

My invention is a combined door-plate and letter-box; and it consists in the peculiar construction, combination, and arrangement of parts, hereinafter described and claimed.

In the drawings, Figure 1 is a sectional view of my invention in place on a door, the latter being also shown in section. Fig. 2 is a rear 15 perspective view of the improvement. Fig. 3 is a detail view of the main plate, and Fig. 4 is a detail perspective view of the name-plate.

The door A has a slit or opening, a, for the 20 passage of letters, papers, and the like, and is provided above said opening with mortises 1, to receive the inwardly-projected bosses b on the main plate B. This plate B has a letter-opening, C, which, when the plate B is 25 properly attached to the door, registers with opening a therein. The bosses b have threaded sockets 2, and openings 3 are formed through the door from its inner side into the mortises 1 for the passage of bolts D, presently described. The main plate has an upward extension at 4, on which may be cast or otherwise suitably exhibited the number or other 30 designation of the particular house or room to which the improvement is applied. At its 35 lower edge the main plate has a portion, E, provided with an opening, e, for a headed stud or screw, F, the head of which receives the stroke of the name-plate in the use of such part as a knocker and bears the wear and damage of such impact. By this means the wear-surface may be renewed at a slight cost and 40 without any considerable trouble, and the main plate will be relieved of all wear.

Slots G are formed from the upper edge of 45 the opening C, and such slots lead into enlarged mortises, forming seats g for the pintles h of the hinge-connection between the main plate and the name-plate H. This plate H has the pintles formed on its upper edge,

and such pintles may be readily moved into 50 and out of their seats in main plate when such plate is removed from the door, but will be locked by the door in said seats when the main plate is attached to the door. I cast or otherwise exhibit on the name-plate the name of 55 the occupant, or such other words, as "For Rent," "For Sale," &c., as may be desirable, and one plate H may be removed by loosening up the bolts which secure the main plate and another attached. Thus when all doors 60 are provided with my improvement a party removing from one house into another may take his name-plate with him, and a "for-rent" plate may be attached to the vacant house. 65

At its lower edge the plate H has a thickened portion, I, which serves several purposes. In the first place it is a handle by which to manipulate the name-plate. It further serves to give weight to the moving edge 70 of and to receive the wear in the use of such plate as a knocker.

The bolts D are passed through openings 3 and threaded into the bosses b, which latter are properly seated in the mortises 1. I form 75 the heads j of these bolts with annular grooves 6, to receive the letter-bag K. This bag is looped at k over the heads of the bolts, and is formed of suitable flexible material, so it will collapse when empty. I provide it with a 80 weight-rod, 7, which, by gravity, serves to keep its mouth properly against the door. Letters dropped through slit a will pass into the bag, which, when filled, may be easily emptied. 85

Now it will be seen that the parts are secured from the inner side of the door, and the main plate and name-plate cannot be removed except by releasing the bolts from the inner side of the door. 90

A special advantage results from the bosses b, inasmuch as thereby I provide long and consequently strong bearings for the fastening-bolts without necessitating the use of an extra thick main plate. 95

Having thus described my invention, what I claim as new is—

The improved device of the character de-

scribed, consisting of the main plate A, having a letter-opening and provided with bosses b, and with a portion, E, having an opening, e, which receives a screw, the projecting head of which receives the blow of the knocker and sustains the wear resulting from the said stroke, the name-plate hinged to plate A and having a portion, I, and the bolts having their

points fitted to be threaded into bosses b and their heads constructed to receive the letter-
bag, substantially as set forth.

WILLIAM ACKIN MOORE.
